UNITED STATES PATENT OFFICE.

ALBERT C. PROHL, OF MILWAUKEE, WISCONSIN.

BOOK-HOLDER OR COPY-STAND.

SPECIFICATION forming part of Letters Patent No. 506,015, dated October 3, 1893.

Application filed May 8, 1893. Serial No. 473,438. (No model.)

To all whom it may concern:

Be it known that I, ALBERT C. PROHL, a citizen of the United States, and a resident of Milwaukee, in the county of Milwaukee, and 5 in the State of Wisconsin, have invented certain new and useful Improvements in Book-Holders or Copy-Stands; and I do hereby declare that the following is a full, clear, and exact description thereof.

10 My invention relates to book-holders and copy-stands, and consists in certain peculiarities of construction and combination of parts as will be fully set forth hereinafter, and subsequently claimed.

15 In the drawings Figure 1 is a perspective view of my improved device, in position for use. Fig. 2 is a plan view of the same, with the parts folded together for storage. Fig. 3 is a rear elevation of the same. Fig. 4 is a 20 detail sectional view, on an enlarged scale, taken on the line 4—4 of Fig. 2.

25 My device comprises a suitable backing A, made of any suitable material, such as a sheet of tin-plate, or other sheet-metal, and which may be lacquered, japanned, painted, or otherwise ornamented. The upper and lower edges, a, b, of this sheet are preferably turned over, as shown, the upper edge a inclosing the upper part of a practically rectangular 30 wire frame, B, made of a single strip of wire, whose ends are bent toward each other, at the said upper part of the frame and concealed by said upper edge a of the backing A, while the corresponding lower part of said

35 wire frame is formed with two loops, c c, to receive the obliquely bent portions e e of the legs or supports of the device, when the same is adjusted into position for use, as shown in Fig. 1. These legs or supports are each made

40 of a single strip of wire, having a vertical or straight portion C, preferably terminating at the bottom in a scroll, or inturned end d forming a foot, these parts C being held to the backing A, by inturned side edges h h of the

45 latter; from the upper end of this straight portion C the wire is continued in an oblique line, forming the portion e, and thence at an obtuse angle f and terminating in an upward angular bend g, the part f forming the other 50 foot of the leg or support when the device is

in use, and the part g bent backward to be parallel with the part e forming the front support of the book or copy.

At points adjacent to the upper and lower portions of the backing A, the side edges thereof are cut to form narrow tongues i i, bent back in a direction opposite to that of the described inturned side edges h h, for the reception of a slate or tablet D, as shown in Figs. 3 and 4. This slate or tablet D may be 60 of any suitable material having an erasable-writing surface, such as stone, paper, celluloid or silicated card-board, and is slipped to place against the reverse side of the backing A, being held between that and the described 65 tongues i i, the lower edge of the slate or tablet resting in the described upturned lower edge b of said backing.

The operation of my device will be readily apparent from the foregoing description of 70 its construction, taken in connection with the accompanying drawings. When not in use, the device can be folded into very compact form, as indicated in Fig. 2, in which condition it will occupy very little space on a desk 75 or table, and when extended, as shown in Fig. 1, makes a most convenient book-holder or copy-stand, the reverse side with the surface D affording an accessible place for any memorandum, or special directions regarding the 80 book or copy upon the front of the device.

Having thus described my invention, what I claim as new, and desire to secure by Letters Patent, is—

1. As an improved article of manufacture, 85 the herein described book-holder and copy-stand, comprising a suitable backing of sheet-metal or analogous material, a wire frame of practically rectangular shape pivotally attached to the inturned upper edge of said 90 backing and having rectangularly projecting loops in its continuous lower portion, and angularly bent wire legs or supports, also pivotally secured to said backing and adapted for engagement with the said loops in the 95 said wire frame, substantially as set forth.

2. As an improved article of manufacture, the herein described book-holder and copy-stand, comprising a suitable backing of sheet-metal or analogous material, a wire frame of 100

practically rectangular shape pivotally secured to said backing by the inturned upper edge of the latter, and having loops in its lower portion, angularly bent wire legs or supports pivotally secured to said backing by the inturned side edges of the latter, and adapted for engagement with said loops in the said wire frame, and having upturned and inwardly inclined outer ends, and a slate or writing tablet secured to the reverse side of said backing by means of tongues cut from

the latter and bent back, and by the upturned lower edge of said backing, substantially as set forth.

In testimony that I claim the foregoing I ¹⁵ have hereunto set my hand, at Milwaukee, in the county of Milwaukee and State of Wisconsin, in the presence of two witnesses.

ALBERT C. PROHL.

Witnesses:
